DRILLING APPARATUS

John C. Curtis, Garfield Heights, Ohio, assignor
to The Cleveland Rock Drill Company, Cleve-
land, Ohio, a corporation of Ohio

Application September 26, 1934, Serial No. 745,616
Renewed October 23, 1937

23 Claims. (Cl. 255—51)

This invention relates broadly to rock drills, but more particularly to a portable drilling rig generally known in the art as wagon drill.

One object of this invention is to produce a portable drilling rig comprising a wheel supported carrying frame having a drilling mechanism mounted thereon for longitudinal slide adjustment relative to the carrying frame.

Another object of this invention is to produce a wheel supported carrying frame having a rock drill supporting frame mounted thereon for pivotal and slide adjustment relative to the carrying frame.

Another object of this invention is to provide a wagon drill with a carrying frame formed with an open end and having a drilling mechanism supporting frame slideable thereon with the drilling mechanism adjustable longitudinally of the carrying frame through the open end thereof.

Another object of this invention is to produce a wagon drill including a carrying frame and a drill supporting frame with simple and efficient connecting means therebetween whereby the drill supporting frame may be adjusted in height and longitudinally of the carrying frame.

Another object of this invention is to provide a wagon drill comprising a carrying frame and a drill supporting frame pivotally connected thereto, with means adjustably mounted on the carrying frame and connectable with the drill supporting frame for effecting the pivotal movement thereof.

Other objects and advantages more or less ancillary to the foregoing and the manner in which the various objects are attained, reside in the specific construction and aggroupment of the elements peculiar to this structure, as will become apparent from a more complete examination of this specification, in the claims of which there are assembled certain specific combinations of parts and specific constructions indicative of the scope and spirit of the invention.

In the drawings which illustrate the invention:

Fig. 1 is a side elevational view of the entire drilling rig illustrating the drilling mechanism in perpendicular relation with the wheel supported frame.

Fig. 2 is an end elevational view of the drilling rig shown in Fig. 1.

Fig. 3 is an enlarged sectional view taken in a plane indicated by line 3—3 in Fig. 1.

Fig. 4 is an enlarged fragmental view of the wheel support as shown in Fig. 2.

Fig. 5 is an enlarged cross sectional view taken in a plane indicated by line 5—5 in Fig. 4.

Fig. 6 is a view similar to Fig. 1 showing the drilling mechanism in another position.

Fig. 7 is a view similar to Fig. 2 illustrating the drilling mechanism positioned for drilling holes in a ditch.

Fig. 8 is a top plan view of the drilling rig illustrating the drilling mechanism in a vertical position, and the wheels located for longitudinal movement of the carriage.

Fig. 9 is a view similar to Fig. 8 illustrating the drilling mechanism in a horizontal position and the wheels located for transversal movement of the carriage.

Referring to the drawings in which like symbols designate corresponding parts throughout the different views, 20 represents a carrying frame preferably formed by two tubular parallel side members or arms 21 and 22 united by a tubular end member or cross arm 23, which is preferably,

rigidly and permanently secured to the side members to form a single unit, of a substantially U shape, having the central portion as well as one end thereof open for the purposes which will be explained later. Affixed to each side members 21 and 22, and preferably near the free end

thereof, there is a casting 24 extending laterally therefrom and secured thereto by bolts 25. The casting 24 is slotted to receive the square end portion 26 of a shaft 27 extending therefrom and on which is rotatably mounted a wheel 28. The square portion 26 of the shaft 27 is pivotally secured within the casting 24 by a bolt 29 transversally disposed through the casting and the square portion of the shaft. Toward its free end,

the square portion 26 is provided with a transversally disposed aperture 30 capable of individual registration with similarly disposed apertures 31 and 32 provided within the casting 24, and adapted to receive a pin 33 by which the shaft 27, and consequently the wheel 28, may be locked against pivotal movement. Secured to the end member 23, there is a bracket 34 having

rotatable therein the shaft portion 35 of a fork shaped support 36, which is provided with a cross shaft 37 having rotatable thereon a small wheel

38. Located above the end member 23 and extending the full length thereof, there is a handle 39 which is welded to the side members of the frame 20.

Carried by the frame 20, there is a three sided tool supporting frame 40 comprising two parallel legs or side arms 40' united at one end by a cross member or arm 40'' constituting a substantially U-shaped member of a lesser width than that of the carrying frame 20. To assure rigidity, the

55

cross arm 40" is welded or otherwise rigidly secured to the legs 40', thus resulting in a tool supporting frame forming a single unit.

The tool supporting frame 40 is disposed transversely of the carrying frame 20 with each leg of the former movably connected to the corresponding side member of the latter through a connection comprising a transversely disposed cone member 41 rigidly secured to the free end of each leg 40'. This cone member is rotatably mounted within a corresponding socket member 42, which is formed with a longitudinally disposed semi-circular seat 43 engaging the corresponding side member of the frame 20. Cooperating with each socket member 42, there is a cap 45 also provided with a semi-circular seat 47 engaging the side member of the carrying frame 20, and forming with the seat 43 sliding bearings for the tool supporting frame 40. Extending from the socket member 42 through its component cap 45, there are two bolts 44 adapted to receive nuts 46 by which the socket member, and consequently the tool supporting frame 40, may be locked on the frame 20 against slidable movement. The cone member 41, and consequently the drill supporting frame 40, may also be locked against pivotal movement relative to the frame 20 by a bolt 48 leading from the socket member 42 through the cone member 41 to receive a nut 49. From the foregoing description, it will be understood that the free ends of the frame 40 are located inside of the carrying frame and are connected thereto by two identical connections each including sliding bearings 43 and 47 which may be clamped on the carrying frame against slidable movement relative thereto, and that the same connections also include pivotal bearings in the form of taper mating surfaces which may be locked against relative rotation.

40 Detachably secured to the cross arm 40" of the tool supporting frame 40 by bolts 50, there is the usual saddle 51 formed with a socket adapted to pivotally receive a cone member 52 which may be locked therein by a clamp 53 and bolt 54. The cone member 52 is integrally affixed to a drill guiding frame 55 at a place substantially equidistant from the ends thereof. This drill guiding frame includes a pair of parallel guides 56 secured to a tube 68 by bolts 57. Slidably mounted within the guides 56, there is a slabback 58 having secured thereto by clamps 59 a fluid actuated drilling motor 60. The tube 68 is adapted to accommodate therein a fluid actuated feeding mechanism capable of imparting feeding motion in both directions to the drilling motor 60 by a flexible member or chain 63, which is connected to the slabback 58 by a clamp 54. The length of this drill guiding frame may be such as to meet any desired condition. In practice it is generally long enough to have its lower end positioned within the open end of the carrying frame when the rig is set for drilling vertical holes as shown in Fig. 1. For purpose of illustration, this drill guiding frame is shown to be of a type similar to the one described in my United States Patent No. 2,029,223, but it is to be understood that any other suitable drilling mechanism, wherein the drilling motor is slidably mounted on a drill guiding frame, could well be substituted for the one above described without departing from the scope and spirit of this invention.

Secured to the frame 20 by a connection 65, which is a replica of the connection shown in Fig. 3, there is a stanchion or post 66 which is movably secured to the cone member 41 by a clamp

67. This post carries a hoisting mechanism for the tool supporting frame 40 including a pulley 70 secured thereto by a hook 69. This pulley is adapted to receive a rope or cable 71 leading from the drum of a hand operated winch 72, which is detachably secured to the stanchion 66 by a clamp 73. To the free end of the cable 71 is affixed a hook 74 capable of engaging the cross arm 40" of the frame 40.

5 Detachably secured to the tool supporting frame 40 by means of a clamp 75, there is an arm 76. Similarly secured to each of the side members of the frame 20 by a clamp 77, there is a rotatable housing 78 adapted to slidably receive an anchoring peg 79, which may be locked 15 therein by a bolt 80. Toward the front end of the tube 68, the latter is provided with a housing 81 welded thereon, and having slidable therethrough an anchoring peg 82, which may be secured in position by a screw 83.

20 In practice, by loosening the bolts 50, the entire drilling apparatus may be rotated and slid on the cross arm 40" of the tool supporting frame 40, that is, on a transversal axis relative to the carrying frame. In other words, the drilling apparatus may revolve around the center 25 axis of the cross arm 40", with at least one end of the drill guiding frame 55 passing through the open end of the carrying frame, thus enabling the drilling apparatus to be positioned 30 either vertically, angularly or horizontally with respect to the carrying frame. By loosening the bolt 54, the entire drilling apparatus may also be rotated on an axis perpendicular to the cross arm 40", allowing thereby the lower end of the 35 drill guiding frame in Fig. 2 to be moved from one of the side members of the carrying frame to the other.

Due to the movable connections between the carrying frame 20 and the tool supporting frame 40, the entire drilling apparatus may be elevated or lowered relative to the carrying frame by simply loosening the nuts 49. To facilitate the raising of the tool supporting frame and checking its downward movement, the hoisting mechanism carried by the post 66 may be connected to the frame 40 by attaching the free end of the flexible member or cable 71 to the cross arm 40" by the hook 74.

50 In practice, it has been found desirable to maintain the weight of the drill guiding frame substantially on the axis of the wheels 28, facilitating thereby the moving of the rig and maintaining the center of gravity inside of the marginal edge of the carrying frame 20. In the 55 present construction, due to the pivotal and slidable connections between the two frames, the drilling apparatus may be adjusted in height relative to the carrying frame, with the weight of the former remaining on the wheels 28. In 60 this instance, the tool supporting frame 40 may be rotated and simultaneously slid on the carrying frame to cause the upward or downward movement of its cross arm 40" within a plane perpendicular to the carrying frame.

65 Due to the movable connections between the two frames, it will be understood that the drill supporting frame is capable of independent pivotal and slidable movements relative to the carrying frame, and may be locked against one of 70 said movements irrespective of the other. To allow the swinging movement of the drill guiding frame resulting either from the pivotal connection between the latter and the tool supporting frame or between the tool supporting frame and 75

the carrying frame, the space between the two cone members 41 has been left unobstructed, thus enabling the swinging movement of the drill guiding frame through the open center and the open end of the carrying frame, and between the legs of the tool supporting frame. It will also be understood that due to the movable connections and the unobstructed space above referred to, the drilling apparatus is adjustable from above 10 to below the carrying frame. Furthermore since the supporting frame 40 is of a lesser width than that of the carrying frame 20, the former may be positioned within the latter to form a substantially flat rectangular structure adjustable 15 in length.

When it is desired to drill in a ditch or trench, the drilling apparatus may be positioned as illustrated in Fig. 7, with the tool supporting frame 40 swung through the carrying frame 20 for positioning the drilling apparatus well into the trench. If the trench is longer than the distance between the wheels 28 and 38, the frame may be supported above the trench by the wheels 28 in straddle relation with the trench, and by 25 25 the anchoring pegs 79 secured to the side members of the frame 20.

The post 66 carrying the hoisting mechanism including the hand winch 72, may be pivoted or slid relative to the carrying frame 20, and may 30 also be rotated on its own axis for locating the hoisting mechanism in the most advantageous position for either elevating, lowering or sliding the tool supporting frame 40 relative to the carrying frame 20.

The entire drilling apparatus may be moved on the ground in a direction transversal to the carrying frame 20, by moving the wheels 28 from the position shown in Fig. 8 to the position shown in Fig. 9. This may be done by simply removing 40 the pin 33 from the hole 32, turning each wheel and shaft 27 until the aperture 30 registers with the aperture 24, then reinserting the pin 33 for locking the wheel in the new position.

When it is desired to drill holes outside of the carrying frame 20, the saddle 51 together with the drill guiding frame 55 may be mounted in the usual manner on the arm 76, which is secured on the tool supporting frame 40 by a clamp 75. By loosening this clamp, the arm 76 may be 50 swung around or slid on the side leg of the frame on which it is mounted, thus permitting the drilling of holes outside of the carrying frame in different directions.

When starting the drilling of a hole, the front 55 end of the drill guiding frame 55 may be secured against movement relative to the work by driving the anchoring peg 82 into the ground, and locking the peg to the housing 81 by tightening the bolt 83.

Although the foregoing description is necessarily of a detailed character, in order to completely set forth the invention, it is to be understood that the specific terminology is not intended to be restrictive or confining and it is to be further understood that various rearrangements of parts and modification of structural detail may be resorted to without departing from the scope or spirit of the invention as herein claimed.

70 I claim:

1. In a drilling apparatus, a mechanism for supporting and guiding a drill comprising a carrying frame, a substantially U-shaped member supported by said frame, connections between 75 said member and frame including tapered mat-

ing surfaces affording the pivotal movement of said member relative to said frame, said connections arranged and disposed in a manner affording the slidable movement of said member relative to said frame, a drill guiding frame detachably secured to the cross arm of said member, and means operable for causing the forcible interengagement of said tapered surfaces for locking said member against pivotal movement irrespective of the slidable movement thereof. 10

2. In a portable drilling rig, the combination of a carrying frame, bearings carried by said frame capable of longitudinal slidable movement relative thereto, a substantially U-shaped tool supporting frame having the free end portion of 15 the side arms thereof pivotally and slidably connected by said bearings to said carrying frame, a rock drilling mechanism supported by the cross arm of said supporting frame, and means forming a part of said bearings for holding said tool supporting frame in adjusted positions, said supporting frame due to the pivotal and slidable connections with said carrying frame being adjustable to position said drilling mechanism in different heights with respect to said carrying frame within a plane perpendicular to the latter. 25

3. In a drilling apparatus, a mechanism for supporting and guiding a drill comprising a carrying frame, bearings carried by said frame in slidable engagement therewith, a substantially 30 U-shaped member having the free end portion of each side arm thereof pivotally and slidably connected by said bearings to said frame, a drill guiding frame detachably secured to the cross arm of said substantially U-shaped member, and means forming a part of said bearings for holding said member in adjusted position. 35

4. In a portable drill rig, the combination of a carrying frame including at least two parallel side members having an open space therebetween, supporting wheels for said frame, a substantially U-shaped tool supporting frame including two side arms and a cross arm, a drill detachably secured to the cross arm of said tool supporting frame and connecting means carried 40 by each of said side members by which said tool supporting frame is connected to said side members and capable of longitudinal slidable and pivotal movement therebetween, said connecting means including means for establishing a rigid 45 connection between said frames in any drilling 50 position assumed by said drill due to the movements of said supporting frame. 55

5. In a portable drilling rig, the combination of a substantially flat carrying frame having an open 55 center, supporting wheels for one end of said frame each rotatable on an axle extending laterally from said frame, the space between said wheels being unobstructed, a substantially U-shaped tool supporting frame including two side legs and a cross 60 arm, slidable connections between the free end portion of said legs and said carrying frame, the space between said slidable connections being unobstructed, a rock drill mechanism supported by said cross arm on an axis perpendicular to the 65 slidable axis of said supporting frame, one end of said drilling mechanism being capable of movement through the open center of the carrying frame and between said wheels and said slidable connections, said drilling mechanism being adjustable longitudinally of said carrying frame due 70 to the slidable movement of the supporting frame, and means for locking the two frames against relative movement. 75

6. In a portable drilling rig, the combination of

- an open ended carrying frame, a substantially U-shaped tool supporting frame including two side members and a cross arm, connecting means between said frames affording the longitudinal 5 slidable and pivotal movement of said supporting frame relative to said carrying frame, a drilling mechanism detachably secured to the cross arm of said supporting frame, said drilling mechanism being movable through the open end of 10 said carrying frame from above to below the latter due to the pivotal movement of said supporting frame and longitudinally through said open end due to the slidable movement of said supporting frame, and means for establishing a rigid connection 15 between said frames in any drilling position assumed by said drilling mechanism by virtue of said slidable and pivotal connection.

7. In a portable rig, the combination of a substantially flat U-shaped carrying frame including 20 two side members and a cross end member, the space between said side members being unobstructed to form an open end portion for said frame extending from the free end of said side members to said cross end member, a wheel 25 secured to the free end of each of said side members for supporting the same, each wheel being rotatable on an axle extending laterally from said frame, a substantially U-shaped tool supporting frame of a lesser width than 30 that of said carrying frame and having a drill supported thereby, the side members of said carrying frame between said wheels and said cross end member constituting guides having the side arms of said supporting frame connected thereto for slidable movement therebetween through the open end portion of said carrying frame, and means for establishing a rigid connection 35 between said frames in any drilling position assumed by said drill by virtue of the 40 slidable movement of said supporting frame relative to said carrying frame.

8. In a portable drilling rig, a carrying frame having an open center portion, supporting means for said frame, a substantially U-shaped tool 45 supporting frame having its legs pivotally and slidably connected to said carrying frame, the space between the pivotal and slidable connections being unobstructed, the possible slidable travel of said supporting frame on said carrying 50 frame being equal to or greater than the length of the former whereby the cross arm of said tool supporting frame is adjustable in height within a vertical plane from a horizontal position of said supporting frame through a vertical position, and means for holding said tool supporting 55 frame in adjusted position.

9. In a portable drilling rig, the combination of a carrying frame, supporting wheels for one end of said frame, the space between said wheels being unobstructed, a substantially U-shaped tool supporting frame having its lower end portion connected to said carrying frame for pivotal and slidable movement relative thereto, a drilling mechanism carried by the upper portion of said 60 supporting frame and extending between said wheels, said drilling mechanism due to the pivotal and slidable movement of said tool supporting frame being adjustable in height relative to said carrying frame in a manner affording the 65 relation between said wheels and the center of mass of said drilling mechanism to remain substantially constant, and means for locking said frames against relative movement.

10. In a portable drilling rig, a substantially U-shaped carrying frame, supporting wheels car- 70

ried by said frame, a substantially U-shaped tool supporting frame carried by said carrying frame, means slidably connecting said tool supporting frame to said carrying frame, said tool supporting frame being located within said carrying frame to constitute in combination therewith a substantially rectangular structure, said structure being adjustable in length by the slidable movement of said supporting frame, and means for locking said frames against relative movement.

11. In a portable drilling rig, a substantially U-shaped carrying frame, supporting wheels carried by said frame, a substantially U-shaped tool supporting frame carried by said carrying frame, means slidably connecting said tool supporting frame to said carrying frame, said tool supporting frame being located with respect to said carrying frame in a manner constituting in combination therewith a substantially flat rectangular structure, said structure due to the slidable movement of said tool supporting frame being adjustable from a length substantially equal to that of the carrying frame through a length substantially equal to the combined length of said frames, and means for locking said frames against relative movement.

12. In a drilling apparatus, a mechanism for supporting and guiding a drill comprising a carrying frame, a drill guiding frame supported by said carrying frame, a connecting member between said frames whereby said drill guiding frame may be secured above said carrying frame in various positions relative to the latter, a hoisting mechanism operatively connectable with said member for moving said drill guiding frame in said various positions, said hoisting mechanism comprising a stanchion having a winch and a rope receiving pulley affixed thereto, and means for securing said stanchion to said carrying frame in different operative positions.

13. In a portable drilling rig, the combination of a carrying frame, a tool supporting frame pivotally connected to said carrying frame, a bearing carried by said carrying frame capable of longitudinal slidable movement relative thereto, a stanchion pivotally and slidably connected by said bearing to said carrying frame, a hoisting mechanism carried by said stanchion and connectable with said supporting frame for causing the pivotal movement thereof, and means forming a part of said bearing for locking said stanchion to said carrying frame in variable operative positions with respect to said supporting frame.

14. In a drilling apparatus, a mechanism for supporting and guiding a drill comprising a carrying frame, a drill guiding frame supported by the latter, a connecting member between said frames whereby said drill guiding frame may be secured above said carrying frame in different positions relative thereto, a post slidably carried by said carrying frame, a hoisting mechanism carried by said post including a flexible element attached to said member for moving said drill guiding frame in different positions, and means for adjustably securing said post to said carrying frame.

15. In a drilling apparatus, a mechanism for supporting and guiding a drill comprising a carrying frame, a member pivotally connected to said carrying frame, a drill guiding frame supported by said member for pivotal movement therewith, a post slidably carried by said carrying frame independently of said member, a hoisting mechanism carried by said post including a

flexible element attached to said member for effecting the pivotal movement thereof in one direction and checking it in the other direction, and means for securing said post to said carrying frame.

16. In a portable drilling rig, the combination of a carrying frame having an open end, supporting wheels for the open end of said frame rotatable on an axle extending laterally from said frame, the space between said wheels being unobstructed, a three sided tool supporting frame including two side legs united by a cross member, a slidable connection below said cross member between each of said legs and said carrying frame enabling the slidable longitudinal adjustment of said tool supporting frame relative to said carrying frame, the space between said connections being unobstructed, a rock drill mechanism supported by said cross member on an axis 20 perpendicular to the slidable axis of said supporting frame, one end of said drilling mechanism being capable of swinging movement through the open end of the carrying frame and between said wheels and said connections, and 25 means for locking the two frames against relative movement.

17. In a portable drilling rig, the combination of a substantially flat U-shaped carrying frame including two parallel side members united by a 30 cross end member, a wheel secured to each of said side members near the free end thereof, a three sided tool supporting frame including two parallel side arms united by a cross member, a drill supported by said cross member, the side members of said carrying frame between said wheels and said cross end member constituting guides each having one of said side arms connected thereto for slidable movement therebetween through the open end of said carrying frame, 40 and means for establishing a rigid connection between said frames in any drilling position assumed by said drill by virtue of the slidable movement of said supporting frame relative to said carrying frame.

18. In a portable drilling rig, the combination of an open ended carrying frame including two parallel side members, supporting wheels secured to and extending higher than said frame, the space between said wheels being unobstructed, a three sided tool supporting frame including two side arms one leading upwardly from each of said side members and united above said carrying frame by a cross member, a drilling apparatus movably supported by said cross member, 50 connecting means between each of said side arms and its corresponding side member enabling the slidable movement of said tool supporting frame longitudinally of said side member for movement of said drilling apparatus between said 55 wheels through the open end of said carrying frame, and means for establishing a rigid connection between said frames.

19. In a portable drilling rig, the combination of a carrying frame, supporting wheels for one end of said frame rotatable on an axis extending laterally from said frame, the space between said wheels being unobstructed, a tool supporting frame including two side arms united by a cross member, a drilling mechanism carried by 65 said cross member and extending between said wheels, individual connecting means between each of said side arms and said carrying frame enabling the slidable movement of said tool sup-

porting frame longitudinally of said carrying frame and the consequential slidable movement of said drilling mechanism between said wheels, and means for establishing a rigid connection between said frames.

20. In a portable drilling rig, the combination of a carrying frame formed with an open end, supporting wheels secured to and extending higher than said frame, the space between said wheels being unobstructed, a three sided tool supporting 10 frame including two side arms united by a cross member, a drilling apparatus carried by said cross member and extending into the open end of said carrying frame, individual connecting means between each of said side arms and said carrying frame enabling the slidable movement of said tool supporting frame longitudinally of said carrying frame and the consequential slid- 15 able movement of said drilling apparatus between said wheels through the open end of said carrying frame, and means for establishing a rigid connection between said frames.

21. In a drilling apparatus, a mechanism for supporting and guiding a drill including a substantially flat carrying frame, supporting wheels 25 secured to and extending higher than said frame, the space between said wheels being unobstructed, bearings carried by said frame in slidable engagement therewith, a three sided tool supporting frame including two side legs united by 30 a cross member, each of said side legs being slidably connected by said bearings to said carrying frame, a drill guiding frame pivotally secured to said cross member for pivotal movement between said wheels and said bearings, and 35 means for holding said frames against relative movement.

22. In a portable drilling rig, the combination of an open ended carrying frame, a three sided tool supporting frame including two side members and a cross arm, connecting means between said frames affording the longitudinal slidable and pivotal movement of said supporting frame relative to said carrying frame, a drill guiding frame carried by the cross arm of said supporting frame, a pivotal connection between said drill guiding frame and cross arm, one end of said drill guiding frame being movable longitudinally and pivotally through the open end of the carrying frame due to the slidable and pivotal movement of said tool carrying frame and pivotally through said open end due to said pivotal connection, and means for establishing a rigid connection between said frames.

23. In a portable drilling rig, the combination of a substantially flat carrying frame including two side members having an open space therebetween, supporting wheels secured to and extending higher than said frame, the space between said wheels being unobstructed, a drill 50 guiding frame capable of longitudinal and elevational adjustments relative to said carrying frame, connecting means between said frames enabling the longitudinal and elevational adjustments of said drill guiding frame between said wheels through the open space of said carrying frame, said connecting means including slid- 55 able bearings in operative engagement with said side members, a mechanism operatively associated with said connecting means for effecting one of said adjustments, and means for locking said frames against relative movement.

JOHN C. CURTIS.
